US00D771050S

(12) **United States Design Patent** (10) **Patent No.:** **US D771,050 S**
(45) **Date of Patent:** **** Nov. 8, 2016**

(54) **FINGERPRINT SCANNER WITH
GRAPHICAL DISPLAY**

(71) Applicant: **JENETRIC GmbH**, Jena (DE)

(72) Inventors: **Dirk Morgeneier**, Jena (DE); **Roberto Wolfer**, Jena (DE)

(73) Assignee: **JENETRIC GMBH**, Jena (DE)

(**) Term: **15 Years**

(21) Appl. No.: **29/540,037**

(22) Filed: **Sep. 21, 2015**

(51) LOC (10) Cl. **14-02**

(52) U.S. Cl. **USPC D14/426**

(58) **Field of Classification Search**

CLAIM

The ornamental design for a fingerprint scanner with graphical display, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top right front perspective view of the fingerprint scanner with graphical display showing our new design in turned-off mode;

FIG. 2 is a top plan view thereof;

FIG. 3 is a left side elevational view thereof;

FIG. 4 is a right side elevational view thereof;

FIG. 5 is a front elevational view thereof;

FIG. 6 is a rear elevational view thereof; and,

FIG. 7 is a bottom plan view thereof.
